DIMMITT ROSS LOVEJOY, OF NEW YORK, N. Y., ASSIGNOR TO LOVEJOY DEVELOPMENT CORPORATION, OF NEW YORK, N. Y., A CORPORATION OF NEW YORK.

TUNED RADIO FREQUENCY CIRCUITS.

Application filed June 4, 1925. Serial No. 34,890.

This invention relates to means for preventing undesired regeneration in radio apparatus using triode tube amplification, and particularly to receiving sets having one or 5 more stages of tuned radio frequency amplification. The object of this invention is to provide means for convenient and exact control of the regeneration which usually occurs when such amplification is attempted.

10 It is well known that radio frequency amplification stages tend to oscillate owing to the various energy feed-backs which are inevitably present. The total value of these energy feed backs varies in each individual 15 set even in sets which seem to be identical and even in the same set with different tubes. These constants may be termed the feed back characteristic of the set. The factors which are involved in this "feed back characteristic" are the amplifying power of the tubes used, temperature of the filament, potential of the grid, potential of the plate and the 20 capacitative and magnetic coupling between the input and output circuits of one or more 25 tubes. In this connection it is convenient to use the expression "base line voltage" to indicate that fixed voltage about whose value the alternating complement varies. It is also 30 well known that excessive regeneration may be prevented by giving the grids of the radio frequency tubes a positive bias with respect to the negative end of the tube filaments. The amount of such positive bias required is not constant but in a given set varies with 35 the frequency which is being amplified, a greater positive bias being required as the frequency increases. A well known means of impressing the proper grid potential consists in the use of a potentiometer, connected 40 across the A-battery, to the moving contact of which is connected the filament end of the grid circuit, the position of the contact being varied empirically and manually so as to give the correct grid bias when the circuits 45 are tuned to a given frequency. This, of course, necessitates an additional adjustment in the process of tuning and since it is practically impossible to predetermine the setting of the potentiometer, the set will inevitably 50 oscillate and squeal if the positive bias is not great enough or else the set will be sluggish, insensitive, inefficient and tune broadly if the positive bias is too great.

55 In general the setting of a potentiometer as used in the above way, bears no relation

to the setting of the tuning means, the correct point on the potentiometer being found by trial and error, the result being that the receiving set usually squeals badly every 60 time it is tuned, to the detriment of good reception and to the annoyance of all radio neighbors.

The necessity of varying the grid bias for different frequencies naturally suggests the desirability of conjoint movement of the 65 potentiometer arm with the tuning control. But due to the varying "feed back characteristic" of each individual set, and indeed with different tubes of the same type, the problem is more complex. I have found, however, 70 that the individual "feed back characteristic" referred to can be compensated for by giving to the potentiometer a voltage gradient corresponding to the "feed back characteristic" of the individual set and tubes at a constant 75 filament temperature, and once this gradient has been adjusted and fixed for that particular set the satisfactory conjoint operation of the potentiometer arm and the tuning control, as by mechanical interconnection, then 80 becomes possible and when so connected maximum efficiency of the receiving set without the possibility of squealing will be assured.

The "feed back characteristic" varies as 85 above stated with the filament temperature. Thus, the filament current would disturb the established coordination above described. Therefore, in receiving sets in which provision is made for varying the filament current, 90 it is necessary to provide additional means to compensate for the changes in the feed back characteristic caused by changes in the filament temperature.

95 My invention comprises means for electrically coordinating the potentiometer gradient to the "feed back characteristic" so that its settings correspond with the settings of the tuning means, to the end that when the two controls are connected and operated by 100 a single knob, the position of the potentiometer contact will be just right to give the proper grid bias for the frequency determined by that setting of the tuning means, thus making it possible for a unit 105 control to give the proper grid bias for all frequencies, hence insuring the quiet, efficient operation of the set. The means employed comprise first a grid potentiometer 110 in combination with means for producing or

providing a desired potential gradient therein. This special potentiometer preferably has its contact arm mounted on the shaft of the tuning control. The potential gradient is so adjusted that the potential at the point of contact is correct at that particular setting of the tuning control. Thus, as the circuit is tuned, the grid bias varies automatically, becoming more positive with respect to the negative terminal of the tube filament as the frequency increases, and becoming less positive as the frequency decreases. In sets in which the filament temperatures may be varied, additional means are provided for compensating for the changes in the feed back characteristic due to changes in filament temperature.

The invention will be more easily understood by a description illustrated by the accompanying drawings, in which—

Figure 1 is a diagrammatic view of a radio circuit.

Figure 2 is a similar view showing additional features, and

Figure 3 illustrates graphically the relation of grid bias characteristics to condenser settings and filament voltages.

In the drawings, C, D and E represent the usual tuning condensers of a 3-tube set having two stages of tuned radio frequency amplification. T is the moving contact of a potentiometer F G, said moving contact being suitably mounted upon the shaft of one of the tuning condensers, as by the extended shaft S of the condenser C. When this condenser is turned in the process of tuning, the contact T moves simultaneously therewith and changes its point of contact upon potentiometer F G.

The grid circuits of C and D are connected to the contact T, so that if the potential gradient in the potentiometer is just right, the contact T will rest upon a point whose potential is of the correct value for the feed back characteristic at that particular setting of the condenser.

In order to adjust the end values of the potential gradient in F G, I prefer to connect it through adjustable contacts J K to a second potentiometer H I which in turn has impressed upon it the potential of the A-battery.

By suitably adjusting the contacts J and K, any potential within the limits of the A-battery may be impressed upon F G, the two ends thereof being separately adjustable. If the resistance of F G is uniformly distributed, the potential gradient therein will also be uniform, i. e. a straight line characteristic. But the changes of grid bias required to prevent oscillations at different condenser settings are not necessarily proportional to the said condenser settings. Therefore, in order that the potential gradient in F G may be properly related to the condenser settings,

it is necessary in some cases that the resistance of F G be not uniformly distributed but properly graduated. This may be accomplished by making the resistance unit F G with a non-uniform winding, but I prefer to use a uniform winding and to vary the potential gradient therein by shunting portions of said uniform winding by additional parallel resistances L, M and N of proper values to vary the potential gradient in a way to conform to the grid bias required in a given case. If desired, the resistance F G may be left uniformly distributed and the condenser settings made to conform to a straight-line relationship by suitably shaping the plates thereof and the same end attained. As the amount of grid bias required to prevent oscillations is not the same at different filament temperatures, less being required as the temperature increases, as shown in Figure 3, it is desirable to provide means for compensation for this variation. In the particular case shown in Figure 3, which is the result of experimental test of a certain definite arrangement of circuits, the grid bias characteristics are nearly straight-lines between condenser settings 10 to 100 and have the same shape for different filament voltages, being practically parallel and separated in this particular case by a practically fixed difference of .15 volt for .5 volt-change in filament potential.

In an arrangement of circuits such as the above, it is clear that a given change in the filament voltage requires a quite definite change in the grid bias to conform to the feed back characteristic and that the amount of this change within limits is nearly independent of the condenser setting. In other words, an increase of filament voltage reduces the absolute value of the whole grid bias characteristic without changing its shape and conversely for a decrease in filament voltage.

In Figure 2 is shown a method of compensation for the above variations. I prefer to use an additional potentiometer X Y shunted across a single cell of battery O and having a movable contact W which is preferably mechanically connected, as shown by the dotted line S to the contact V of the filament rheostat Q R so as to be operated synchronously therewith. As the contact V moves to the left to increase the filament current, the contact W also moves to the left and so includes in the grid return circuit less positive bias from the potentiometer X Y, and therefore the grid bias characteristic as shown in Figure 3 is moved downward without changing its shape.

With the potential gradient in X Y properly adjusted with reference to the effect of motion of contact V on the filament voltage and to the corresponding position of con-

tact W, it will be readily seen that the required fixed difference in the grid bias characteristics is easily obtained and such difference is independent of the change produced by the motion produced by contact T of potentiometer F G.

I claim:—

1. In a tuned radio frequency amplifying circuit using an audion and a tuning element, means for automatically varying at different frequencies the value of the base-line voltage of the grid in a direction and to an extent suitable to offset the change of the remaining factors of the feed back characteristic occurring at such change of frequencies, for the purpose of maintaining maximum efficiency throughout the frequency range, said means comprising a potentiometer having its movable contact connected electrically to the grid and mechanically interconnected with the tuning element and a second potentiometer for adjusting the potential gradient of the first mentioned potentiometer connected across a source of potential which in turn is connected to the filament.

2. In a tuned radio frequency amplifying circuit using an audion, a tuning element and a filament rheostat, means for auto-

matically varying at different frequencies 30 and filament temperatures the value of the base-line voltage of the grid, in a direction and to an extent, suitable to offset the change of the remaining factors of the feed back characteristic occurring at such change of 35 frequencies and filament temperatures, said means comprising a potentiometer having its movable contact connected electrically to the grid and mechanically interconnected with the tuning element and a second 40 potentiometer for adjusting the potential gradient of the first mentioned potentiometer, connected across a source of potential which in turn is connected to the filament, and a separately energized potentiometer 45 actuated by the filament rheostat and connected with the first mentioned potentiometer, for varying the grid potential determined by the setting of said first mentioned potentiometer, so as to add to or subtract 50 from the potential obtained therefrom an amount equal to the change in the grid potential required by the change in filament current, for the purpose of maintaining maximum efficiency throughout the frequency range. 55

DIMMITT ROSS LOVEJOY.
